DESIGN FOR A CASING FOR A FLUID METER COUNTER OR SIMILAR ARTICLE

Eugene W. Shafer, San Mateo, Calif., assignor to
Ralph N. Brodie Company, Oakland, Calif., a
corporation of California

Application April 11, 1938, Serial No. 76,416

Term of patent 7 years

To all whom it may concern:

Be it known that I, Eugene W. Shafer, a citizen of the United States, residing at the city of San Mateo, county of San Mateo, State of California, have invented a new, original, and ornamental Design for a Casing for a Fluid Meter Counter or Similar Article, of which the following is a specification, reference being had to the accompanying drawing, forming part thereof.

Fig. 1 is a plan view of a casing for a fluid meter counter, showing my new design;

Fig. 2 is a front elevational view thereof;

Fig. 3 is an end elevation thereof.

I claim:

The ornamental design for a casing for a fluid meter counter or similar article, substantially as shown.

EUGENE W. SHAFER.
